United States Patent Office

Des. 194,473
Patented Jan. 29, 1963

194,473

COMBINED MIXER AND STAND

John E. Reed, Glen Ellyn, Ill., assignor to Sunbeam Corporation, Chicago, Ill., a corporation of Illinois

Filed July 13, 1962, Ser. No. 70,907

Term of patent 14 years

(Cl. D44—1)

Fig. 2.

FIG. 3.

FIG. 4.

FIG. 5.

FIG. 1 is a perspective view of a combined mixer and stand embodying my design;

FIG. 2 is a side elevational view thereof;

FIG. 3 is a sectional view taken along line 3—3 of FIG. 2;

FIG. 4 is a front elevational view thereof; and

FIG. 5 is a rear elevational view thereof.

I claim:

The ornamental design for a combined mixer and stand, as shown.
